UNITED STATES PATENT OFFICE.

DONALD PARKER, OF LOS ANGELES, CALIFORNIA.

ELEVATING MEANS FOR SORTING TABLES.

Application filed August 28, 1923. Serial No. 659,749.

To all whom it may concern:

Be it known that I, DONALD PARKER, a citizen of the United States, residing at Los Angeles, in the county of Los Angeles 5 and State of California, have invented certain new and useful Improvements in Elevating Means for Sorting Tables, of which the following is a specification.

The present invention relates to elevating means for use in connection with roller bed sorting tables employed in connection with the handling of boxes of filled fruit to be sorted. In this type of sorting tables the filled boxes of fruit to be sorted are 10 successively advanced over the roller bed of the sorting table and brought to sorting stations of the sorting table which are arranged at spaced intervals on one or both sides of the table throughout the length thereof. At 15 each sorting station there is arranged adjacent the side walls of the table a longitudinally disposed idler roller, over which roller the boxes of filled fruit are drawn onto the sorting stations as the boxes are laterally withdrawn from the roller bed of the sorting table, it being required that the 20 sorters raise the boxes of filled fruit clear of the roller bed of the sorting table in order to place the same onto the longitudinally disposed roller over which the boxes 25 are drawn and moved from the roller bed of the sorting table onto the sorting station. The sorters are thus required to lift the weight of the filled box, thus placing a 30 somewhat heavy load onto the sorters.

The object of the present invention is to provide means whereby the boxes of filled fruit when positioned at a sorting station, may be easily and expeditiously raised a 35 slight distance above the plane of the transversely disposed rollers constituting the roller bed of the sorting table and positioned for free and easy withdrawal onto the longitudinally disposed rollers situated adjacent 40 each sorting station, said elevating means serving as roller feed for aiding or assisting in the lateral withdrawal of the boxes of filled fruit and to support and carry the weight thereof, whereby the sorters situated 45 at the sorting stations are relieved of the necessity of lifting the weight of the filled boxes.

To comprehend the present invention ref-

erence should be had to the accompanying sheet of drawings wherein—

Fig. 1 is a plan view partly broken away of an ordinary conventional type of a roller bed sorting table, with the present invention applied thereto at the respective sorting stations.

Fig. 2 is a cross sectional elevation taken on the line 2—2, Fig. 1 of the drawings, the position of the elevating means when in raised position being disclosed in dotted lines.

In the drawings, the numeral 1 designates any suitable form of a frame structure for the sorting table and 2 the transversely disposed rollers arranged therein and constituting the roller bed of the sorting table. At spaced intervals along one or both sides of the sorting table is arranged an aligned series of sorting stations 3, at which is adapted to be positioned a sorter for the filled boxes of unsorted fruit. Adjacent each sorting station and mounted within suitable bearing brackets 5 are longitudinally disposed rollers 6, over which rollers the boxes of filled fruit are withdrawn laterally from the roller bed of the sorting table onto the platforms of the sorting stations. Secured at each sorting station to the frame of the sorting table there is located a bracket 7, the lower extension of which is swung inwardly to a position beneath the roller bed of the sorting table. To each of these brackets is pivoted in the present case a foot actuated lever 8, which at its free inner end carries a short longitudinally disposed shaft 9, upon the ends of which shaft are mounted for free rotation and in spaced relation the elevating rollers 10. These rollers are located beneath the roller bed of the sorting table and are so positioned with respect to the transversely disposed rollers thereof as to move between said rollers when thrown in elevated position by depressing the lever 8, the upward movement of the rollers 10 being such that the same when in elevated position have the surfaces thereof a slight distance above the plane of the roller bed of the sorting table.

As a filled box of unsorted fruit is advanced over the roller bed of the sorting table and brought to a state of rest at a sorting station, the said box will be positioned immediately above the elevating rollers 10

and when it is desired by the sorter to remove the box of filled fruit from off the roller bed of the said table onto a sorting platform, the lever 8 is depressed, which 5 raises the rollers 10 between the rollers of the sorting table bed and raises the box slightly above the same, so that at such time the weight of the filled box is mainly brought to bear onto the freely mounted 10 rollers 10. The operator is then only required to exert a slight pulling strain onto the boxes 11 of filled fruit which causes the same to ride over the rollers 10 onto the longitudinally disposed delivery roller 6, over 15 which the box moves onto the sorting table or platform 12, the operator thus being relieved of the necessity of bodily lifting the weight of the filled boxes to place the same from the roller bed of the sorting table onto 20 the transversely disposed roller 6.

While I have disclosed a foot actuated lever 8 for controlling the raising of the elevating rollers 10, it is obvious that any means may be utilized for this purpose and 25 I therefore do not wish to be understood as restricting the actuating means to a foot operating lever and while the inwardly extended portion of the actuating lever 8 terminates in a forked or yoke bearing extension 30 for the shaft of the rollers 10, any other desired form may be employed for supporting the said rollers.

The invention has been described in its 35 preferred embodiment of cooperating details of construction, but I do not wish to be understood as limiting or restricting the invention as described to the details of construction, but wish to be understood as claiming the invention as broadly as the 40 state of the art will warrant, the said invention residing in box elevating means adapted to be thrown into an elevated position in order to raise a filled box of unsorted fruit above the plane of the roller bed of the sorting table and to serve as 45 means for aiding and assisting the movement of the box from the roller bed onto the longitudinally disposed roller positioned at each sorting station for receiving the said

box of fruit and advancing the same from 50 the sorting table onto the sorting platforms.

Having thus described my invention, what I claim as new and desire to secure by Letters Patent, is:

1. The combination of a roller bed runway provided at spaced points throughout its length with material withdrawal stations, a material supporting roller at each withdrawal station disposed in proximity to the ends of the bed rollers at the station 60 and at substantially right angles thereto, means for elevating the material from the roller bed runway at each withdrawal station, each means including a pair of disks mounted to rotate on an axis parallel with 65 that of the roller at each withdrawal station, means for mounting said disks normally below the surface of the roller bed runway, and a manually connected lever associated with said mounting means for guiding the same to project said disks upwardly between the rollers of said runway with their periphery above the surface of the bed 70 of said runway.

2. The combination of a roller bed runway provided at spaced points throughout its length with material withdrawal stations, a material supporting roller at each withdrawal station disposed in proximity to the ends of the bed rollers at the station and at 75 substantially right angles thereto, means for elevating the material from the roller bed runway at each withdrawal station, each means including a roller mounted to rotate 80 on an axis parallel with that of the roller at each withdrawal station, a pivotally mounted frame supporting each roller and normally disposing the same with its periphery below the surface of the bed, a pedal depending from each frame and adapted for 85 actuation to project the elevating roller upwardly between adjacent rollers of the bed 90 with its periphery above the surface of the bed.

In testimony whereof I have signed my name to this specification.

DONALD PARKER.
